UNITED STATES PATENT OFFICE.

COLLINGWOOD POLLARD, OF BRADFORD, ENGLAND.

DESIGN FOR A KINDLING-BLOCK.

SPECIFICATION forming part of Design No. 35,686, dated February 4, 1902.

Application filed December 18, 1901. Serial No. 86,421. Term of patent 14 years.

To all whom it may concern:

Be it known that I, COLLINGWOOD POLLARD, a subject of the King of Great Britain, residing at Bradford, England, have invented and produced a new and original Design for a Kindling-Block, of which the following is a specification, reference being had to the accompanying drawings, forming part thereof.

In the drawings, Figure 1 represents a plan view of the kindling-block, showing one side or face. Fig. 2 is a view of the opposite face. Fig. 3 is a view of one edge of the block, while Fig. 4 is an end view.

The leading or material feature of the design consists in the outline configuration, which is practically that of a diamond.

As shown in Fig. 1, the block is composed

of an integral piece of wood comprising a series of diagonal ribs *a* with intervening spaces *b* and having the outline that of a diamond. 20

In Fig. 2 the opposite face is made up of a series of smaller ribs *c*, with intervening spaces *d*.

In Fig. 3 is shown a view of the block from the side of Fig. 2, and in Fig. 4 is shown an 25 end view of Fig. 2.

I claim—

The design for a kindling-block as herein shown and described.

COLLINGWOOD POLLARD.
